UNITED STATES PATENT OFFICE

1,995,912

WASHING MACHINE

Vincent G. Apple, Dayton, Ohio; Herbert F. Apple, Edward M. Apple, and Gourley Darroch, executors of said Vincent G. Apple, deceased

Application June 14, 1928, Serial No. 285,373

3 Claims. (Cl. 192—135)

My invention relates particularly to that type of washing machine comprising a frame having mounted thereon a tub adapted to contain water and within which a perforated cylinder containing the clothes is revolved alternately in one and the other direction to agitate the contents thereof, and as the cylinder must needs have an opening thru which the clothes may be entered and removed and a lid for keeping such opening closed during rotation and as the cylinder may preferably be disconnected from the power source to bring it to rest, one object of my invention is to provide a simple mechanism whereby the cylinder driving means may be connected to the power source when desirable but may be disconnected therefrom only when the lid covering the opening in the cylinder is at the top and in the most advantageous position, the disconnecting means serving further to keep the cylinder locked in such position while disconnected. Another object of my invention is to provide a reversing mechanism having fewest parts consistent with effectiveness and safety in operation. Another object is to so distribute the several parts of the mechanism about the frame as to maintain a better state of equilibrium than is usually found in machines of this type.

Other objects will become apparent to those skilled in the art as the invention is described in detail and reference is made to the drawings, wherein—

Fig. 1 is a plan view of my machine.

Fig. 2 is a cross section taken on line 2—2 of Fig. 6.

Fig. 3 is a cross section taken on line 3—3 of Fig. 8.

Fig. 4 is a front elevation of my machine shown in outline only.

Fig. 5 is a cross section thru the gear case taken on line 5—5 of Fig. 6.

Fig. 6 is a right hand end view, a cross section being taken thru the operating mechanism as on line 6—6 of Figs. 4 and 5.

Fig. 7 is a cross section taken on line 7—7 of Figs. 4 and 5.

Fig. 8 is a left hand end view with a portion of the housing removed to show the reversing means.

Figs. 9, 9a and 9b show the clutch mechanism drawn to a larger scale.

Figures 10, 11 and 12 show detail parts of the clutch mechanism.

Similar numerals refer to similar parts throughout the several views.

Referring to the drawings a frame 10 carries

a tub 11 which contains the water or other washing medium. A perforated cylinder 12, supported at one end on pivot 13 and at the other end on the squared end of shaft 14 is thus adapted to be revolved within the tub. Shaft 14 is mounted to revolve in bearing 15 which is part of housing 16. Pinion 17 at the outer end of bearing 15 and within housing 16 is adapted to drive shaft 14. A bar 18 carries at one portion thereof rack teeth 19 adapted to engage the teeth of pinion 17 and at another portion it has bearing on crank pin 20 of crank 21. Crank 21 is securely mounted on shaft 22 supported in bearing 23 which is part of housing 16.

Shaft 22 is adapted to be driven constantly in the same direction to revolve crank 21 thereabout. A roller 24 mounted on stud 25 securely fastened in housing 16 bears in curved groove 26 of member 18 to suitably hold the rack teeth 19 in contact with pinion 17 at any position of crank 21.

It is readily seen that when shaft 22 revolves crank 21, crank pin 20 moves member 18 in one direction during substantially one half revolution of said shaft and in the other direction during substantially the other half revolution of said shaft to revolve pinion 17 first in one direction then in another.

Shaft 22 extending horizontally under tub 11 is supported in bearing 27 which is part of housing 28. Mounted free to revolve on shaft 22 and within housing 28 is a driving member for the shaft 22 comprising a bevel gear 29 the web 30 of which is depressed and bored smooth as at 31 except for a notch 32 in the inner diameter. Securely fastened to shaft 22 is a pawl carrier comprising a hub 33 having arms 34 and 35 and a lug 36 extending therefrom. Arms 34 and 35 are bored at their outer end to receive hinge pin 37. Free to rock on hinge pin 37 are pawl 38 and pawl control arm 39. Pawl 38 and pawl control arm 39 are bodily revolvable about the shaft 22 by the pawl carrier. Pawl 38 has a lug 40 which closely fits into notch 32. An opening 41 extends through the body of the pawl. Pawl control arm 39 has a lateral projection 42 extending loosely into opening 41, providing a lost motion connection between the pawl 38 and the pawl control arm 39. Projection 42 has a pocket 42a therein (see Fig. 11) which carries spring 43, the free end of which bears against the inner diameter of opening 41 of pawl 38 thus keeping the lateral projection 42 against one side of said opening. A raised portion 44 of pawl control arm 39 extends outwardly therefrom and a spring 45 is held in

compression between lug 46 of pawl control arm 39 and lug 36 of hub 33. Spring 45 urges pawl control arm 39 outwardly, pushing the lateral projection 42 against the outer side of opening 41, thus urging pawl 38 outwardly to press its lug 40 into the notch 32 of the constantly rotating gear 29.

A cam 47 having a stem 48 which has bearing in housing 28 is adapted to be moved to one or the other of two positions, the one position being shown in Fig. 9 at 47 and the other in Fig. 9a at 47'. By means of a handle 53 secured to stem 48, cam 47 may be moved to one or the other position as desired. A bevel pinion 54 mounted on shaft 55 having bearing in housing 28 drives bevel gear 29. While I prefer that shaft 55 be connected to a power unit such as I show in my co-pending application Serial Number 285,369 it may be connected to any other power source placed anywhere about the machine if so desired.

In operation the constantly rotating bevel gear 29 drives its notch 32 against the lug 40 of pawl 38 and thereby turns shaft 22 by means of pawl 38 which is mounted on the hub 33 secured to the shaft. When it is desired to stop oscillation of cylinder 12 handle 53 is moved to bring cam 47 to the position 47' Fig. 9a whereupon the raised portion 44 of pawl control arm 39, revolving about shaft 22, will come into contact with cam 47' to depress pawl control arm 39. Pawl control arm 39 then compresses spring 43 until its lateral projection 42 moves to the opposite side of opening 41 after which it will carry pawl 38 with it. Further depression of pawl control arm 39 then drags lug 40 from notch 32 of bevel gear 29 until lug 40 is entirely disengaged from notch 32, whereupon spring 43 will again expand, thus moving the lug 40 entirely free from surface 31 of gear 29, whereupon shaft 22 will be at rest and the cylinder will cease to revolve.

It will be noticed from the drawings that the several parts of the machine may be so arranged that at the instant the power is thus disconnected the opening 58 in cylinder 12 will be on top and that the crank 21 will be on dead center so that no amount of effort manually exerted on cylinder 12 could turn crank 21 to move pawl 39 out of contact with cam 47. When however, by handle 53 cam 47 is returned to its normal position lug 40 will be quickly returned by spring 45 into notch 32 to again revolve cylinder 12.

A tube 57 threaded at both ends joins bearing 23 and 27 and encloses shaft 22 so that oil supplied to one housing may gradually work thru tube 57 to maintain the supply in the other thus simplifying the oiling system and guarding against oil being deposited on any exposed portion of the machine, and the weight of the mechanical parts being distributed over both ends of the frame keeps the machine in equilibrium when a wringer of the swinging type is brought to extend to a position beyond the tub.

Having described my invention, I claim:

1. Clutch mechanism comprising, in combination, a driven shaft, a driving member freely rotatable about said shaft, a hinge pin bodily revolvable about said shaft, means rigidly secured to said shaft to support said hinge pin, a pawl and a pawl control arm hinged on said hinge pin,

a spring adapted to urge the free end of the pawl control arm outwardly away from the shaft, a lateral projection on the first said pawl extending into an opening in the said pawl, said opening being somewhat larger than said projection, a second spring adapted to urge said lateral projection outwardly against the outer side of said opening, a lug at the free end of the said pawl, a notch in the freely rotatable driving member adapted to receive said lug, a raised projection near the free end of the said pawl control arm, and a cam adapted to be manually extended into the orbit of said raised projection.

2. In combination, a frame, a rotatable shaft having bearing in said frame, a driving member rotatable freely on said shaft, and mechanism for establishing driving relation between said driving member and said shaft and for interrupting said driving relation always at the same predetermined point in the rotation of said shaft, said mechanism comprising a pawl carrier secured to said shaft to revolve said shaft, a pawl hinge pin in said carrier revolvable by said carrier in an orbit about the axis of said shaft, a pawl and a pawl control arm swingable side by side on said hinge pin, a cam mounted on said frame manually movable into and out of the orbit of said pawl control arm to push said pawl control arm from said orbit, resilient means holding the free end of said pawl control arm in its normal orbit, means connecting the pawl and pawl control arm whereby swinging of the pawl control arm swings the pawl into and out of contact with the driving member, there being lost motion in the connecting means whereby the pawl or pawl control arm each may swing a limited distance without swinging the other, and resilient means carried by the said pawl control arm tending to swing the said pawl out of contact with the said driving member when said pawl control arm is being pushed from its orbit by said cam.

3. In combination, a drivable shaft, a driving member freely rotatable on said shaft, and mechanism to connect said driving member to said shaft to drive said shaft and to disconnect said driving member from said shaft always at the same position in the rotation of said shaft, said mechanism comprising, two members bodily revolvable in an orbit about the axis of said shaft, a carrier secured to said shaft to revolve in unison therewith and to carry said bodily revolvable members, resilient means urging one of said bodily revolvable members in one direction out of its normal orbit, a stationary cam manually insertable into the orbit of the one said bodily revolvable member to push said member oppositely out of its orbit, means on said driving member to engage the second said bodily revolvable member to carry said second bodily revolvable member around its said orbit, a lost motion connection between the two bodily revolvable members, and resilient means interposed between the two said bodily revolvable members urging the second said bodily revolvable member away from the engaging means on said driving member when the first said bodily revolvable member is being pushed out of its orbit by said cam.

VINCENT G. APPLE.

CERTIFICATE OF CORRECTION.

Patent No. 1,995,912.

March 26, 1935.

VINCENT G. APPLE, deceased; whose EXECUTORS are HERBERT F. APPLE,
EDWARD M. APPLE, and GOURLEY DARROCH.

It is hereby certified that error appears in the printed specification of the above numbered patent requiring correction as follows: Page 2, second column, line 3, claim 1, strike out the word "first" and in the same line, after "pawl" insert the words control arm; and that the said Letters Patent should be read with these corrections therein that the same may conform to the record of the case in the Patent Office.

Signed and sealed this 11th day of June, A. D. 1935.

(Seal)

Leslie Frazer
Acting Commissioner of Patents.
